UNITED STATES PATENT OFFICE.

JOHN B. GAVIN, OF CHICAGO, ILLINOIS, ASSIGNOR TO FREDERICK C. AUSTIN,
OF SAME PLACE.

GRADING AND DITCHING MACHINE.

SPECIFICATION forming part of Letters Patent No. 394,534, dated December 11, 1888.

Application filed April 24, 1888. Serial No. 271,725. (No model.)

To all whom it may concern:

Be it known that I, JOHN B. GAVIN, a citizen of the United States, residing at Chicago, in the county of Cook and State of Illinois, have invented certain new and useful Improvements in Grading and Ditching Machines, of which the following is a specification.

My invention relates more particularly to the devices by which the elevator-belt in a grading and ditching machine can be driven from the rear main supporting-wheels, the objects of my said invention being to facilitate the running of the machine; to provide simple and efficient means whereby the rear axle may be lubricated; to provide a simple, compact, and desirable arrangement of parts; to economize space; to permit a driving-chain employed for operating a belt-roller at one end of the elevator to be extended back in a convenient way under the body-frame of the machine; to provide a simplified arrangement for supporting and lubricating a rotary shaft that is driven from the wheels and provided with a clutch for the purpose of connecting or disconnecting the power, and to provide certain improved details of construction, hereinafter particularly specified.

To the attainment of the foregoing and other useful ends my invention consists in matters hereinafter described, and particularly pointed out in the claims.

In the annexed drawings, Figure 1 represents a rear end elevation of so much of a grading and ditching machine as may be necessary to illustrate my invention. Fig. 2 is an end view of one of the flanged sleeves that are adapted to be driven into the hubs of the rear wheels and provide supports for the pawls. Fig. 3 is an end view of one of the hubs or collars that are provided with ratchets for the aforesaid pawls. Fig. 4 is a side view of the flanged sleeve of Fig. 2. Fig. 5 represents on a somewhat larger scale a horizontal section through the clutch and devices for operating the shaft I, from the rear axle of which latter a portion is shown. Fig. 6 represents a section taken through the box H on a line parallel with the axis of shaft I, Fig. 5. Fig. 7 is a rear elevation of said box.

In said drawings, A indicates the body-

frame, and B the rear wheels, of a grading and ditching machine, which is herein understood to further comprise any suitable arrangement of plow C and any suitable construction of elevator for receiving the soil from the plow and carrying the soil to a point where it is desired to deliver it. 55

The elevator D is shown arranged transversely to the line of progression of the machine, and is extended under the body-frame, so as to bring its receiving end into position to receive the soil from the plow when the latter is suspended at one side of the machine. The length of the elevator is desirably such that 60 it may also extend beyond one side of the machine so far as may be necessary to bring its delivery end at a point proper for discharging the soil that has been carried up the elevator by the endless elevator-belt. 70

The rear wheels, B, are arranged loose upon a rotary axle, F, with which the wheels will be connected during the advancement of the machine, but, preferably, permitted to run loose in backing. This connection between 75 the axle and the wheels can be established by any suitable arrangement of pawl-and-ratchet device—as, for instance, the wheels may carry the pawls, while the ratchets can be secured upon the axle. The rotary axle has its bearings in boxes which are rigid with the body-frame of the machine and adapted to provide suitable lubricant-chambers, wherein a suitable quantity of cotton or other like waste and a suitable lubricant can be contained. 80 85

The boxes G can be rigidly connected with the rear bolster or body-frame by bars, brackets, or in any suitable way, and are each provided with a receptacle adapted to contain a suitable quantity of any desired lubricant. 90 The box H, like the boxes G, is provided with a chamber or receptacle, h, to contain a suitable quantity of lubricant, and is further provided with a bearing, h', for one end of a shaft, I, which is included in a power-transmitting mechanism adapted for effecting the operation of an endless chain that in turn serves to operate the endless elevator-belt. The box is therefore made substantially T-shaped, and is further provided with a chamber or opening, h², wherein lubricant may be received for lubricating the shaft I. 95 100

The boxes G and H can all be clipped upon a lower bar of the rear axle, or connected in any other suitable way with the body-frame. The large bevel-gear K is fixed upon the axle 5 and arranged to engage a gear, i, upon the shaft I, in which way, during the advancement of the machine, the rear axle will be rotated by the rear wheels, and will in turn operate the shaft I through the medium of the 10 intermeshing gears K and i.

The rotary shaft I, which is supported at its rear end in the lateral bearing on the box H, is at its forward end supported from the main frame of the machine by any suitable 15 hanger or brace-support, and carries an ordinary clutch, L, which latter can be operated by a suitably-arranged hand-lever. The shaft I, or one of the clutch-sections, is provided with a suitable sprocket, l, for the endless chain 20 E, which passes around said sprocket, and also passes around a sprocket that is secured upon the axle or one of the journals of a belt-roller at the upper end of the elevator. In this way, when the two sections or glands of the clutch 25 are in engagement with one another, the endless elevator-belt will be driven from the rear axle. The movable section or gland of the clutch can, if desired, be made bell-shaped, so as to more effectively exclude dirt, said form, 30 however, being exceedingly old in clutches.

As a further feature of improvement, the upper half of the box H is herein rigid with a stand, M, which can be cast in one piece with the upper half of the box. This stand 35 serves as an exceedingly efficient connection between the box and the main body-frame, and is also of service where the gear K, in place of being adjacent to the wheel that is at the side of the machine from which the elevator extends, is arranged toward the opposite 40 wheel, it being observed, in this connection, that since the weight of the extension portion of the elevator is at one side of the machine the driving-power should be taken from the 45 axle at a point toward the opposite side of the machine in order to insure proper balance. The stand M may comprise either a single bar or may be of the shape herein shown, and, preferably, the driving-gear K is secured 50 to the axle at a point alongside the box H, whereby the axle will at such point have its bearing in a box that is rigidly connected with the main frame through the medium of the stand M.

55 As a simple way of connecting the rotary axle with the rear wheels during the advancement of the machine, a ribbed sleeve, N, can be driven into each wheel-hub and adapted to form a bearing for the axle. Each one of 60 these sleeves N is at its inner end provided with a flange, n, to which one or more pawls n' can be pivoted. A ratchet, P, is provided for each pair of pawls upon the flange n, and each of said ratchets is in rigid connection with 65 the rear axle. Each ratchet is preferably

formed in the recessed end portion of a hub, p, that is bolted to or otherwise secured upon the rear axle, in which way the pawls and ratchets are concealed and protected from dirt.

70 Where the driving-gear K is arranged as herein shown, the boxes G can be clipped upon the lower bar, a, of the rear bolster, which may be regarded as a part of the body-frame. For certain purposes, however, of this invention all of the boxes—that is to say, the boxes G and the box H—could be clipped or otherwise secured upon the said lower bar, a, of the bolster. It will also be observed that the box H is provided with a suitable lid or cover, 80 h³, for its lubricant-receptacle h, and that a similar or suitable cover can be provided for closing the opening h² to the lubricant-receptacle that is provided for the shaft I. It is also understood that covers can be provided 85 for closing the lubricant-receptacles of the boxes G, which are herein understood to be provided with chambers or receptacles similar to the chamber or receptacle h of the box H.

90 What I claim as my invention is—

1. In a grading and ditching machine, the axle-box H, constructed with a bearing for the driving-axle, and a lateral extension having a bearing, h', for a rotary shaft which is 95 included in a mechanism for transmitting power from the driving-axle to an endless soil-conveyer belt, said box being provided with a lubricant-chamber, h, adapted to receive cotton waste and opening within the 100 cylindric bearing for the driving-axle, and a lubricant-chamber, h², adapted to receive cotton waste and opening within the cylindric bearing for said rotary shaft, substantially as described.

105 2. In a grading and ditching machine, the combination, with the body-frame, of the rear axle, F, a box in which said axle has a bearing, and a stand, such as hereinbefore set forth, rigid with the said box and secured to the body-frame, substantially as set forth.

110 3. In a grading and ditching machine, the combination, with the rear axle, of the rear wheels loose upon said axle, the flanged sleeves N, fitted within the hubs of the rear 115 wheels and carrying pawls, and the ratchets P, rigid with the rear axle, substantially as set forth.

120 4. The combination, with the rear axle, which is supported by and driven from the rear wheels, of a box providing a bearing for the rear axle and rigid with a stand, M, and the driving-gear K and connection therefrom to the elevator-belt, said gear being secured upon the rear axle at a point alongside said box, 125 substantially as set forth.

JOHN B. GAVIN.
